his Attorney.

UNITED STATES PATENT OFFICE.

FREDERICK HENRY ROYCE, OF DERBY, ENGLAND, ASSIGNOR TO ROLLS-ROYCE LIMITED,
OF DERBY, ENGLAND.

LUBRICANT-RETAINING DEVICE FOR THE VALVE MECHANISM OF INTERNAL- COMBUSTION ENGINES.

1,225,361.

Specification of Letters Patent.

Patented May 8, 1917.

Application filed September 19, 1916. Serial No. 121,071.

To all whom it may concern:

Be it known that I, FREDERICK HENRY ROYCE, a subject of the King of England, residing at Derby, in England, have invented certain new and useful Improvements in Lubricant-Retaining Devices for the Valve Mechanism of Internal-Combustion Engines, of which the following is a specification.

10 This invention relates to an improved means for retaining the lubricating oil in casings containing moving parts which project therethrough and require lubrication, more especially the cam-shaft casing of internal combustion engines fitted with overhead valves, and through the sides of which casings oscillating levers or rockers project, and it has for its object the prevention of oil leakage at the points where the said levers 20 pass through the casing.

This end is attained by forming a baffle plate around the projecting element at the point where it passes through the side of the casing, the shape of said baffle plate being 25 such that it forms a pocket which traps any oil tending to creep along the element and enables it to be led back into the casing by means of a suitably shaped and positioned conduit.

30 In the accompanying drawings, which illustrate by way of example the invention applied to the cam-shift casing of an internal combustion engine fitted with overhead valves, Figure 1 is an elevation, partly 35 in section, and Fig. 2 a plan, partly in section (looking in direction of arrow α).

In said drawings c designates the lubricant container or casing in which is mounted the cam-shaft c^2 from which the rocking 40 tappet levers a actuating the valve spindles a^1 are actuated.

The rocking lever a mounted in the casing c is fitted with a plate b which may be formed out of the material of said rocker or

made a separate part and secured to the 45 rocker in any suitable manner, said plate being shaped so that it forms a pocket or baffle which catches any oil creeping along the lever. Over the opening in the casing through which a lever a passes is formed a 50 chamber or channel d into which the oil from the pocket passes and is conveyed back into the casing c through a suitable hole c^1 in the casing wall.

What I claim as my invention and desire 55 to secure by Letters Patent of the United States is:—

1. In an internal combustion engine having overhead valves the combination of a cam shaft casing adapted to contain lubricant, a cam shaft therein, levers operated by said cam shaft adapted to actuate the valves and extending through said casing, and plates on said levers forming baffles adapted to prevent lubricant tending to creep along 60 said valve levers from passing to the exterior of said casing.

2. In an internal combustion engine the combination with a cam-shaft casing adapted to contain lubricant and having an aperture in its wall, a valve operating lever projecting through said aperture, a baffle plate in connection with said lever adjacent said aperture and adapted to arrest lubricant 65 passing therethrough, a second aperture in 70 the casing wall and a conduit exterior to the casing and in communication with said second aperture and the baffle plate for conducting lubricant from the latter back to the 75 interior of the casing.

In witness whereof I have signed this specification in the presence of two witnesses.

FREDERICK HENRY ROYCE.
